UNITED STATES PATENT OFFICE.

JOHN O. SQUIRES AND JOSEPH K. SHRIVER, OF BALTIMORE, MARYLAND.

GUARD FOR MOLDING-MACHINES.

SPECIFICATION forming part of Letters Patent No. 293,534, dated February 12, 1884.

Application filed December 26, 1883. (No model.)

To all whom it may concern:

Be it known that we, JOHN O. SQUIRES and JOSEPH K. SHRIVER, both of the city of Baltimore, and State of Maryland, have invented 5 certain Improvements in Wood-Molding Machines, of which the following is a specification.

This invention relates to a device to be applied to a molding-machine to protect the 10 hands of the operator against the revolving cutters, as will hereinafter fully appear.

In the accompanying drawings, forming a 15 part hereof, Figure I is a front view of the invention. Fig. II is a side view of Fig. I. Fig. III is a top view of the invention. Fig. IV is a top view of the device modified in construction. Figs. V and VI are views of the device further modified.

Referring to Figs. I, II, and III, A is the 20 table, and B the spindle, of the machine. The cutters, which are denoted by a, are secured between nuts b on the spindle B.

C is a guard, supported by the standard D, which, together with the guard, is slotted for 25 the reception of the bolt c. The guard C is formed of a strip of iron bent so as to have a

rounded end and two parallel straight sides, which are connected rigidly together by a brace, d. The guard and standard being slotted, the former may be adjusted in position 30 to suit cutters of different sizes, and also turned up or back, as shown in dotted lines, Fig. II. The guard is placed slightly above the cutters, or elevated sufficiently above the table to admit of the board or piece to be molded being 35 operated upon.

In Fig. IV two standards are used, and in Figs. V and VI a single standard is employed, and the brace slotted and united to the standard by means of a bolt. 40

We claim—

In a molding-machine, the table A, the vertical slotted standard D, attached rigidly to the table, the slotted guard C, having a curved 45 end, and parallel sides connected by a stiffening-brace, and the bolt c, all combined substantially as and for the purpose specified.

JOHN O. SQUIRES.
JOSEPH K. SHRIVER.
